UNITED STATES PATENT OFFICE.

KAREL EDUARD EHRMANN, OF BAJOENG LENTJIR, SUMATRA.

APPARATUS FOR PUMPING OIL FROM PETROLEUM-WELLS.

No. 919,142.

Specification of Letters Patent.

Patented April 20, 1909.

Application filed November 22, 1907. Serial No. 403,412.

To all whom it may concern:

Be it known that I, KAREL EDUARD EHRMANN, a subject of the Queen of the Netherlands, residing at Bajoeng Lentjir, Sumatra, Dutch East Indies, have invented certain new and useful Improvements Relating to Apparatus for Pumping Oil from Petroleum-Wells, of which the following is a specification.

- 10 This invention relates to apparatus for pumping liquid from petroleum-wells and the like, in which the petroleum or other liquid is raised by compressed air. In these wells, the compressed air is supplied by
15 means of a compressed air pipe and the supply of air is regulated in accordance with the capacity of the spring. If no more liquid is delivered, it is said that the well is blown out and the air-supply must then be shut off.
20 The compressed air is then used for another well. With insufficient supervision, it may happen that it is noticed when too late, that the well is running empty, or the supply of compressed air may be forgotten entirely,
25 whereupon the level of the liquid rises but the output of the well is reduced. The apparatus forming the subject of the present invention is designed to prevent this, since it is possible thereby to control the level of
30 the liquid. A controlling device is lowered into the well simultaneously with a "Mammoth" or other suitable air-lift pump, between the compressed-air and oil-delivery pipes. The position of the controlling device,
35 and thus the distance at which it is arranged from the pump, is determined practically for each well. The controlling device comprises a small sheet metal box, in the open bottom of which a small float can move
40 freely up and down. The float is connected by means of a thin rod with a switch-lever which, in the highest position of the float, brings two contacts into engagement with each other. The two contacts are connected
45 by means of insulated wires with an electric bell and indicator board which are arranged in the engine-room or the like. As soon as the liquid in the well has risen up to the level of the float, the electric circuit is completed, the bell sounds, and the number corresponding to this well is exposed on the indicator-board. The engine-attendant is thus notified that compressed air is to be supplied to that particular well.
50 The improved apparatus moreover comprises a shut-off device which is inserted into
55

the compressed air-pipe and enables the engine-attendant, by electrical means to shut off or permit the supply of compressed air at will. This arrangement consists essentially of a box, in which there is a shut-off valve actuated by clockwork, which when locked or released by an electromagnet, closes or opens the valve in accordance with the current supplied thereto. As soon as it is necessary to supply air to a well, the attendant switches the electromagnet into an electric circuit, whereby the air shut-off valve is opened and so remains until the electromagnet is again actuated, when the valve is again closed. This arrangement is moreover in communication by means of insulated wires with the float in the well and with a separate switch-board, whereby it is possible for the engine-attendant to have all 75 the wells under observation from the engine-room and to make arrangements with the official at the well by telephone.

In the accompanying drawings, there is shown one example of construction of the 80 controlling or indicating device and of the shut-off device for the air.

In these drawings Figure 1 is a vertical section through a well having the controlling device fitted thereto. Fig. 2 is a vertical 85 section and Fig. 3 a top view, both drawn to an enlarged scale, showing the controlling device. Fig. 4 is a diagram of the connections of the apparatus, showing one electric circuit. Fig. 5 is a front elevation of the air 90 shut-off device with the front cover removed. Fig. 6 is a vertical section thereof on the line x y, Fig. 5, seen from the left. Fig. 7 is a diagram of the electrical connections of the two arrangements for a complete plant. 95

The plant consists as is known of a bore-hole 1, which is lined with a tube extending to the petroleum stratum, and contains an oil-delivery or discharge pipe 2 and a compressed air pipe 3. These two pipes are 100 connected at their lower end by the known foot piece 4 of a "Mammoth" pump. The lining tube 5 of the well is perforated at its lower end. The liquid level shown by means of the line I, II, in Fig. 1 may be that down to 105 which the liquid is lowered during working. In the upper part of the well is provided a chamber 7.

The controlling device proper is arranged at a predetermined position 6, Fig. 1, between the two pipes 2 and 3 and consists essentially of a casing 8 (Fig. 2) which has

a trapezoidal cross-section with two side walls curved in such a manner that the casing 8 can be conveniently gripped between the two pipes 2 and 3. A partition 9 divides the casing into two similar compartments 10 and 11. The upper chamber 10 is closed by a cover 12. On this cover is fastened a block of insulating material 13 which fits exactly into the upper chamber 10 and on which the contact device is arranged. This device consists of a metal terminal 14 which has a contact spring 15. A contact lever 16 is pivotally mounted on the pin 17 which is mounted on the angle-bracket 18. Through the insulating block 13 extend insulated wires 19 and 20; the wire 19 is connected to the terminal 14, while the wire 20 is connected to the angle-bracket 18. In the lower chamber 11 is arranged a float 21 which is suspended on a thin rod 22 in such a manner that it can move freely. The rod 22 can move freely through the partition 9 and is pivotally connected at its upper end to the contact lever 16. The arrangement of the connections is shown in Fig. 4; the controlling device 8 is connected by means of the conductor 19 to an indicator-board 23, which is connected to an electric bell 24 and a battery 25. The conductor 20 is connected to an earth-plate in a known manner and the battery is earthed in a similar manner. The two conductors are preferably secured to insulators and extend upward along the oil-delivery pipe 2 (Fig. 1) to the chamber 7 whence the circuit can be continued by means of bare wires.

The air shut-off device is built into the air-pipe in any suitable manner. The said device consists essentially of a box 26, which is fastened by means of two metallic side walls to the ends of the compressed-air-pipe 3 (Fig. 5). In the box is arranged the shut-off valve 27 which is intercalated into the compressed-air-pipe in any suitable manner (Fig. 6). The spindle of the valve 27 is extended outwardly and is connected on one side to clockwork 28 and on the other side to a releasing device. The latter consists of an escapement-wheel 29 provided with four teeth, which wheel is controlled by the armature 30 of an electromagnet 31, which is adjustably suspended on the cover of the box. Near the escapement wheel, there is arranged on the extended shaft or spindle a switch-disk 32, the side surface of which consists of insulating material and is intersected by a copper strip 33. On the cover 34 of the box 26 are provided two contact-pins 35 and 36, which are arranged exactly at a right angle 60 relatively to each other. The middle of the strip 33 is directly connected to a bracket-contact 37, which is connected to the electromagnet (Fig. 5). From the electromagnet a wire is led to a terminal 38 arranged on the 65 cover.

The diagram of connections of a complete plant for a number of wells is shown in Fig. 7. The switch-board 39 contains a double interrupter 40, an indicator-board 23, a plug-switch 42, and a pressure-gage 43. The interrupter consists of a copper bar 44, on which, for example, three spring levers 45 are provided corresponding to the number of the wells. This bar is connected to the terminal 41. The contact-plates 46 below are each connected to a terminal 47, while moreover contact-levers 48 are provided which can be connected to the contact-plates 46. The levers 48 are connected to the indicator-board 41, the numbers of which correspond to the lowermost switch-board terminals 49. The battery 25 is similarly earthed, a part thereof is connected by a line wire 51 to the terminals 49, while the outermost carbon electrode is connected to the terminal 41. A telephone apparatus 50 is connected on the one hand to the earth plate of the battery 25 and on the other hand to the plug-switch 42 which latter is likewise connected to the wire 51. In the well C is arranged the controlling device 8. The wire 19 is connected to the terminal 35 and the wire 20 is connected to the terminal 36 and is also earthed. The terminal 38 is connected by means of the line wire 52 to one of the terminals 47. For the other wells A and B similar wires 53 and 54 are provided which are each connected to a terminal 47. In order to enable the official at the well to communicate with the engine attendant, the movable microphone 55 can be earthed on one side and connected on the other side to one of the line wires 52.

The operation of the improved controlling device is as follows: So long as the level of the liquid takes up the position I-II (Fig. 1), the float 21 will remain in its lowermost position and no contact will be made. If by reason of insufficient supervision, the pressure of the compressed air falls or entirely ceases, the level of liquid, which has sunk during working, will rise. The petroleum will rise up to the position 6 (Fig. 1) and come into contact with the float 21; if the rise continues, the float will be raised and the contact-lever 16 will come into contact with the contact-spring 15 whereby the circuit between the wires 19 and 20 will be completed (Fig. 2). By this connection of the contacts 15 and 16, the current will flow through the wire 20 to the indicator-board 23, through the bell 24 to the battery 25 and thence to earth and through the wire 20 back to the controlling device (Fig. 4). It will be seen that the bell will warn the engine-room attendant and the indicator board will indicate to him at the same time the particular well which requires compressed air. If the whole plant works without an air shut-off device, as shown in Fig. 4, the

official can then immediately take steps to supply air to the well or to blow the same empty and shut off the air-supply. By supplying compressed air in a suitable manner, *e. g.*, as hereinafter described, the level of liquid is again depressed and, by the sinking of the float, the controlling device is automatically switched out.

If shut-off devices are provided for the air, 10 the whole plant is more complicated, but the engine-attendant is in a position to regulate exactly the amount of air supplied without leaving his place. This air shut-off device works in the following manner: 15 The clockwork 28 tends to set the spindle of the valve 27 in rotary motion; the armature-pawl 30 however locks the escapement-wheel. If the armature is attracted, the escapement-wheel and therefore also the 20 valve can turn until, by deenergizing the electromagnet, the armature again locks the escapement-wheel. If the air shut-off valve is open, it will be closed on the moving forward of the escapement-wheel through a 25 tooth, in which operation the contact-strip 33 is correspondingly turned through a right angle and now the pin 36, instead of the pin 35 comes into contact with the contact-strip 33. During this movement, the 30 valve has been closed. The electromagnet is so made that its armature is only lifted by a predetermined current.

The operation of the complete plant is as follows:—If the level of liquid has risen in 35 the well C, the circuit in the controlling device 8 is closed between the wires 19 and 20 (Fig. 7). By this means, the current flows from the battery 25 through the wire 51 to the terminal 49, from here to the indicator-board 23, where it causes the number corresponding to the well C to be shown, now flows through the lever 48 (which is in the dotted position), the contact-plate 46, terminal 47, line wire 52, terminal 38, 40 through the electromagnet 31 to the terminal 37, copper strip 33, terminal 35, line wires 19 and 20 to the earth-plate and through the earth back to the negative pole of the battery. This current is too weak to 45 actuate the electromagnet 31 and only causes the number C corresponding to the well to be indicated. The engine-attendant 50 is by this means given a visual signal that the well C needs air, obviously an alarm-bell 55 can also be connected in the circuit. The official now puts the lever 48 into the position shown in full lines in Fig. 7. If the pressure-gage shows sufficient pressure, the attendant presses for an instant the spring 60 lever 45 against the contact-plate 46, whereupon a second circuit is closed. By means of this connection, a current flows from the battery 25 to the terminal 41, through the copper strip 44, the spring lever 45, the contact plate 46, terminal 47, wire 52, terminal

38; through the electromagnet 31, contacts 37, 35, controlling device 8 and through the earth back to the battery. Consequently current from the whole of the battery passes through the electromagnet, whereupon the 70 armature is attracted and the clockwork is released. Since the official only closes the circuit for an instant, the armature immediately falls back again, but the spindle moves until the next tooth of the escapement-wheel is engaged by the detent on the armature. The escapement wheel has therefore turned through 90° and the shut-off valve has been opened. When the official has supplied the prescribed amount of air, he again 80 presses the lever 45, whereupon the whole battery current is again sent through the electromagnet. Since the copper strip 33 has consequently been also turned through 90°, the current flows from 38, through 37, 36 85 and earth back to the battery. By this means, the air shut-off valve is again closed and a fresh cycle of operations can be commenced, for which purpose the official finally returns the lever 48 to its original position. 9

Communication between the official at the well and the engine-attendant takes place in the following manner:—If in the first place a connection is made between the microphone 55 and one of the line wires 52, 53 or 54, the corresponding number appears on the indicator-board. The engine-attendant now switches in the telephone apparatus 50 by means of the plug-switch 42, whereupon communication takes place through 50, 42, 49, 48, 46, 47, 52, 55 and earth. Since actuation of the indicator-board can thus take place by means of the controlling device or of the microphone, the engine-attendant is in a position to switch in the telephone apparatus when the inspector makes his daily round to wind up the clockwork. 105

The whole supervisory apparatus is characterized by simplicity and capacity of being easily inspected, since it can be determined 110 at any time at a central station whether any and which wells require air and whether a sufficient amount of air is available. Moreover the yield of the wells can be much increased, since now efficient working can take 115 place even during the night by the air-controlling device.

What I claim is:—

1. A controlling device for petroleum wells comprising a movably mounted contact, a fixed contact coacting with said movable contact, an air supply pipe, an air valve, means for actuating said air valve, a detent for controlling the movement of said valve actuating means, an electromagnet for actuating said detent, a two-way rotary electric switch connected to said air valve, two electric switches, an electric signaling device, two sources of electricity arranged in series with each other, an electric circuit including 125

130

one of said sources of electricity, said fixed and movable contacts, said rotary switch, said electro-magnet, a branch circuit extending between said rotary switch and said 5 sources of electricity and arranged as an alternative circuit to that through said fixed and movable contacts, and two branch electric circuits one of which comprises one of said electric switches and an additional 10 source of electricity, and the other of which comprises the electric signaling device and the other of said electric switches, substantially as described.

2. A controlling apparatus for petroleum-wells of the kind wherein the petroleum is raised by compressed air, said apparatus comprising a casing supported in said well, a contact movably mounted in said casing, a float connected to said movable contact, a 15 fixed contact coacting with said movable contact, an air-valve, clockwork for actuating said air-valve, a detent for controlling the movement of said clockwork, an electromagnet actuating said detent, a two-way rotary 20

electric switch connected to said air-valve, two electric switches, an electric signaling device, two sources of electricity arranged in series with each other, an electric circuit including one of said sources of electricity, said fixed and movable contacts, said rotary 25 switch, said electromagnet, a branch circuit extending between said rotary switch and said source of electricity and arranged as an alternative circuit to that through said fixed and movable contacts, and two branch electric circuits one of which comprises one of 30 said electric switches and an additional source of electricity, and the other comprises the electric signaling device and the other of said electric switches, substantially as described.

In testimony whereof I have hereunto set my hand in presence of two subscribing witnesses.

KAREL EDUARD EHREMAN.
